UNITED STATES PATENT OFFICE.

ALEXANDER McDougall, OF DULUTH, MINNESOTA.

VESSEL.

1,157,022.

Specification of Letters Patent. Patented Oct. 19, 1915.

Application filed February 14, 1914. Serial No. 818,649.

To all whom it may concern:

Be it known that I, ALEXANDER McDougall, a citizen of the United States, residing at Duluth, in the county of St. Louis and State of Minnesota, have invented certain new and useful Improvements in Vessels, of which the following is a specification, reference being had therein to the accompanying drawing.

10 This invention consists of certain improvements in vessels and relates particularly to a self propelled one, as used for passenger and package freight service and sometimes known as express steamers.

15 For a comprehensive consideration of the objects of my present invention the history of vessel construction may be briefly considered.

When ships were made of wood, and sails used as a means of propulsion the ends of the vessel were made higher than the middle, with the object of keeping the waves off, which resulted in such a vessel suffering most in a head sea or in running before a storm. In these vessels the decks were protected by bulwarks to keep the seas off and to protect the sailors when on duty, and the bottoms were usually much cut away or of rounded form.

20 As iron came into use for ship construction and steam for motive power the form of the vessel remained much the same, even though they have been built much larger and longer. In the larger vessel the tendency has been to increase the heights of the ends, with the same object of keeping off the waves and, to provide the required longitudinal strength and to stand higher out of the water, they have been made much deeper,

25 all of which causes the vessel, when in rough seas, to oscillate both endwise and sidewise, there being such a large proportion of the vessel out of water and upon which the force of the waves is exerted, combined with the momentum of the vessel to cause such action.

To overcome the effects of this abnormal condition and particularly to prevent rolling of the vessel, what are known as bilge keels have been resorted to, these being out-

30 wardly projecting keels usually placed upon the rounded portion of the bottom of the vessel. These, however, being necessarily so small, have not proven particularly efficient. The pitching of a large vessel in rough weather may result in the bow or stern ris-

ing and falling to the extent of fifty feet or over, and the rolling motion may be in proportion, caused chiefly by the high freeboard and results in the speed and utility of the vessel being impaired and also causing abnormal stresses upon the structure of the ship and materially affecting the durability thereof. Now, after twenty years study of the McDougall whale-back type of vessel, with its rounded bottom and top and straight deck throughout and, when deep loaded, low freeboard, which, contrary to the former construction, invites the seas on board and thus partially overcomes the objectionable pitching and rolling; and after 40 careful study of buoyant forms such as the waterlogged ship with decks awash, and the deeply loaded hopper bottomed mud scow in a seaway with its decks awash, and seeing how little water crosses its deck and it remaining apparently steady until its cargo is discharged, after which it rises high out of the water and tosses about like all vessels with comparatively high freeboard, this being caused by the action of the waves against 45 the high sides, and having little stability below the disturbed water line, I have been impressed with the necessity of a radical departure in ship construction.

45 A floating iceberg does not roll or pitch by 50 the action of the waves, as the disturbed surface of the water quickly spends its force in the splash and but very little boards the solid mass.

The large ship rising high out of the 55 water forward and proportionally sinking aft results in a tremendous sucking drag to its forward motion, and then plunging her bow deep into the solid sea with her stern and propeller practically out of water again 60 impedes her motion, besides severely straining the ship, all of which it is extremely desirable to avoid.

50 Careful study of all of these facts has led to my present invention of a fast and steady 65 passenger and express steamer, the object of which is to overcome as nearly as possible many of the objectionable features above related and produce an unusually seaworthy vessel.

55 In the accompanying drawings; Figure 1 is a side elevation of my improved ship. Fig. 2 is a top plan view of the same. Fig. 3 is a cross section through one of the boiler rooms practically amidships.

1 represents the forward end of the hull of the vessel, formed a sharp wedge shape in plan view for speed, and preferably with square bilges 2 to prevent rolling and as a 5 substitute for bilge keels. The midship section is preferably substantially rectangular in cross section, having a slightly inclined convex bottom 3, straight vertical sides 4—4, and a straight horizontal deck 5 the entire length of the vessel, though having the 10 usual camber athwartship, and the lower after end 6 of regular ship form with fine lines for speed and easy leaving of the water.

A vertical central bulkhead 7 extends the 15 entire length of the hull and from the bottom 3 to the deck 5 dividing the hull into practically two equal parts. A plurality of cross bulkheads 8 upon either side of the central bulkhead may be arranged as desired to divide the hull into longitudinal compartments and the required number of 20 between decks 9 as necessity demands.

A deflecting or bulwark turret 10 is formed by an upward extension of the extreme bow for the purpose of breaking the 25 force of seas as they may attempt to board the bow, and a somewhat similar turret 11 is built upon the stern and for a similar purpose. Main intermediate turrets 12, 30 preferably of circular form, are strongly built upon the deck 3 and, together with a suitable number of strong iron pipes 13, support the superstructure 14 of the vessel and are so arranged as to permit of free 35 passage of any water crossing the deck 3, the turrets being equipped with suitable water tight doors and passage ways, arranged to be readily closed in the event of rough weather or they may be made to automatically close in case of accident.

I would suggest, for a very large ship, that the height of the turrets and pipes would be approximately ten feet to provide proper clearance. I would also provide a water 45 tight casing 15 about all of the stacks, to doubly insure their safety.

The superstructure or cabin 14 is designed to be securely riveted to the turrets and pipes and forms an integral structure therewith and is of a construction similar to that of the hull and is practically a second or auxiliary hull mounted upon the major hull, having flat bottom, square bilges and straight sides of steel construction, also 55 similar to the major hull.

Steel decks 16 may divide the auxiliary hull vertically with cross bulkheads 17 arranged as required, thus practically forming two navigable hulls, one superimposed 60 upon the other and each having sufficient reserve buoyancy to support the other in the event of abnormal conditions arising to require such reservation.

The inner wall and bulwarks of the auxiliary hull may be of lighter steel construc-

tion than that of the outer walls and bottom, but of sufficient strength to materially stiffen the side walls against any splash of waves that might reach them. The lighting facilities for this upper hull may consist of 70 the regular water tight deadlights, or other suitable form of water tight windows.

Upon the upper hull or superstructure may be constructed the usual cabin 18 of any construction desired.

Thus I have formed a ship of substantially two lower hulls and one upper hull superimposed thereon by a row of turrets and pipes, the combined buoyancy of the 75 turret, pipes and upper hull being sufficient 80 to support the ship if more than half of the lower hull is full of water, and thus we have a ship moderately free from the dangers of fire or sinking after collision with icebergs or other vessels, or stranding, or, in other 85 words, practically the unsinkable ship. This construction admits of greater and more convenient boiler, engine and fuel capacity than in ordinary ships and the symmetrical form throughout is evidently 90 of much cheaper and stronger construction.

I have shown a working turret 19 intermediate the bow turret 10 and the first superstructure supporting turret 12, which may carry a spar 20 and from which any 95 cargo manipulating device may be operated, such as a boom or the like. The upper deck of this turret communicates with the superstructure 14 by means of the elevated passageway 21.

Having thus described my invention what I claim and desire to secure by Letters Patent is;

1. A vessel comprising a navigable hull substantially rectangular in midship cross 105 section, a wedge shaped forward end with vertical sides throughout, a stern having its underquarters well cut away and a superimposed rectangular shaped cabin carried by the hull and substantially the same width 110 thereof.

2. A vessel comprising a navigable hull substantially rectangular in midship cross section, a wedge shaped forward end with vertical sides throughout, a regular ship 115 shape stern portion, a superstructure spaced above the hull and supported upon a plurality of cylindrical shaped members.

3. A vessel comprising a navigable hull substantially rectangular in midship cross section, a wedge shaped forward end with vertical sides throughout, a cut-away ship shape stern, a superstructure spaced above the hull, turrets supporting the superstructure in such a manner as to expose the larger 125 portion of the main deck of the hull to the wash of abnormal seas.

4. A vessel comprising a hull substantially rectangular in cross section throughout, except in its lower after quarters which are 130

cut away in regular ship shape form, a central bulkhead dividing the hull into two equal parts longitudinally, fixed turrets mounted upon the hull and supporting a 5 superstructure of a construction similar to that of the hull and turrets.

In testimony whereof I affix my signature in presence of two witnesses.

ALEXANDER McDougall.
